(57) **CLAIM**

The ornamental design for a clamping connector, as shown and described.

DESCRIPTION

FIG. 1 is a top and right side perspective view of a clamping connector showing my new design;

FIG. 2 is an exploded top and right side perspective view thereof wherein the end portion is removed for ease of illustration;

FIG. 3 is a right side elevation view thereof without the end portion of FIG. 2;

FIG. 4 is a cross-section taken along line 4—4 of FIG. 3;

FIG. 5 is a front elevation view thereof drawn at a reduced scale;

FIG. 6 is an exploded top plan view thereof drawn at a reduced scale and wherein the end portions are shown for ease of illustration;

FIG. 7 is a rear elevation view thereof drawn at a reduced scale; and,

FIG. 8 is a bottom plan view thereof drawn at a reduced scale.
